DESIGN FOR A SIGN

Merrick Hanchett, Holland, Mich., assignor to Holland Federal Baking Co., Holland, Mich., a corporation of Michigan

Application February 24, 1934, Serial No. 50,853

Term of patent 14 years

To all whom it may concern:

Be it known that I, MERRICK HANCHETT, a citizen of the United States, residing at Holland, in the county of Ottawa and State of Michigan, have invented a new, original, and ornamental Design for a Sign, of which the following is a specification, reference being had to the accompanying drawing, forming part thereof, in which:

Fig. 1 is a front elevation, and
Fig. 2 is an edge elevation of a sign, showing my new design.

I claim:
The ornamental design for a sign, as shown.

MERRICK HANCHETT.
